UNITED STATES PATENT OFFICE.

ANDREW F. ROBINSON, OF ARLINGTON, MASSACHUSETTS, ASSIGNOR TO STANDARD OIL COMPANY OF NEW YORK, OF NEW YORK, N. Y., A CORPORATION OF NEW YORK.

TANK WAGON.

Application filed March 19, 1920. Serial No. 367,252.

To all whom it may concern:

Be it known that I, ANDREW F. ROBINSON, a citizen of the United States, residing at Arlington, in the county of Middlesex and 5 State of Massachusetts, have invented certain new and useful Improvements in Tank Wagons, of which the following is a specification.

This invention relates to vehicles and particularly to vehicles of that class commonly called tank wagons or trucks and it has 10 for its object to improve the construction thereof.

Tank wagons of the kind referred to are 15 used in transporting and dispensing liquids such as gasoline, kerosene, etc., the body of the vehicle consisting of a large sheet iron tank at the rear end of which is provided one or more, usually several, faucets through 20 which the contents of the tank body can be drawn off into measures in making deliveries to customers. These faucets are connected with one or more outlets at the bottom of the tank body by pipes and it is customary 25 to provide valves within the body by means of which the said outlets may be closed to prevent accidental escape, or leakage at the faucets. These valves are manually operated through means which extends upwardly through the top of the tank to the exterior of the latter, and it is intended and usually made a strict rule that said valves be in open position only while a delivery 30 is being made to a customer, and be left in closed position while the vehicle is travelling from one place of delivery to another. In order to do this, however, it is necessary for the person in charge to climb up onto the vehicle both immediately before and 35 immediately after making a delivery in order to reach the valve operating means, which is objectionable, being troublesome and inconvenient for the person in charge. Therefore, it is common practice for the 40 latter, to disregard this rule and when starting upon his route open the valves, and to leave them in that condition until he has completed all of the deliveries throughout the route covered by him. Frequently upon 45 occasions of this kind it has happened that one or more of the faucets have been accidentally or maliciously opened thus permitting the discharge of gasoline from the tank. It has also happened that a tank 50 wagon containing gasoline and travelling 55

through a city street with its valves open, has been struck in the rear by another vehicle with the result that the faucets of the tank wagon were broken off permitting the contents of the latter to discharge onto the 60 roadway, where it caught fire, destroyed the wagon and endangered other property as well as lives. The main object of my invention is to obviate the objectionable features 65 pointed out above and to provide simple, reliable and efficient means for ensuring the closing of the valves after each delivery so to prevent the discharge of the contents of the wagon if the faucets are accidentally or maliciously opened, or broken off through 70 collision with another vehicle.

To these ends the invention consists of a tank wagon having the peculiar features of construction and mode of operation set forth in the following description and particularly pointed out defined in the claims 75 at the close thereof.

In the accompanying drawings:—

Figure 1 is an elevation of the rear end 80 of the body of a tank wagon or vehicle having combined therewith an embodiment of my invention.

Figure 2 is a side view of the rear end portion of the wagon or vehicle.

Figure 3 is a section on line 3—3 of 85 Fig. 1.

Figure 4 is an enlarged view of a portion 90 of the structure shown in Fig. 3.

Figure 5 is a section on line 5—5 of 95 Fig. 4.

Figure 6 is a section on line 6, 6, of Fig. 2, and Figure 7 is a section on line 7—7 100 of Fig. 6.

Wagons or vehicles of the class to which my invention relates comprise a tank body 105 1 made from sheet metal constructed at its rear end with a compartment 2, commonly termed a bucket-box within which are stored the measures or other vessels used in making deliveries to customers, said compartment 100 being separated from the liquid holding compartment 3 by a partition or wall 4. The compartment 2 is normally closed as usual, by a pair of doors 5, 5 connected by hinges 6 with body 1, a fastening device, herein constituted by a latch 7 pivotally mounted upon the outside of one door and 110 engaging a keeper 8 fastened in place upon the outside of the other door, serving to lock said doors in closed positions. Just be-

low the compartment 2 are the usual faucets 9 connected by pipes 10 with the liquid holding compartment 3. Upon arriving at a place of delivery the driver unfastens the 5 fastening device 7, opens doors 5, removes from compartment 2 the measures he is to use, draws off the required amount of liquid at faucets 9 and delivers the same to the customer, replaces the measures within compartment 2, and, after closing and locking the doors 5, moves on to the next place of delivery. As will be clear it is necessary for the driver to open doors 5 in order to obtain the measures and it is also necessary 10 for him to close and lock the doors 5 after replacing the measures in order to avoid loss of the same while traveling over the road.

In carrying out my invention I provide 20 a safety organization having as its main characteristic the fact that it ensures that when the closure of the compartment occupies its closed position, the outlet valve of the tank likewise shall be in its closed position; a second characteristic being the 25 fact that when the closure occupies its closed position the said valve cannot be opened. Stated in general terms, the invention comprises means ensuring a closed condition 30 of the outlet valve when the closure of the bucket-box is closed, and providing, through the opening of the closure, for the opening of the valve. The invention may be carried into effect variously, by different mechanical organizations and combinations.

In the present illustrated embodiment I locate within compartment 2 a bracket 11 bolted, or otherwise secured, to the rear wall 12 of body 1 just above one of the doors 5. 40 This bracket 11 is made with a downwardly projecting arm 13 occupying a position immediately behind said door 5, said arm being provided with a vertical slot 14 within which is arranged the hub 15 of a valve 45 operating lever 16, said hub being pivotally connected with arm 13 by means of a pin 17. The hub 15 is made with a radial flange 18, the periphery of which is formed with two notches 19 and 20, angularly positioned 50 ninety degrees apart. These notches cooperate with a latch member 21 pivotally secured by a pin 22 within another slot 23 provided at the lower end of arm 13, said slot 23 being at right angles to slot 14. The 55 hub of latch 21 is notched at its periphery to provide a passage 24 through which flange 18 is free to swing when said passage 24 is alined with said flange, while the portion 60 of said hub at one side of said notch is adapted to enter and occupy either notch 19 or 20. Opposite the lever locking portion 65 the latch 21 is made with a radial downwardly extending arm 26 which serves both as a handle by means of which said latch is manually swung upon its pivot 22 and as

a weight for holding latch 21 in lever-locking position. Stops 27 and 28 projecting radially from the hub portion of latch 21 are adapted to engage the sides of flange 18 of lever 16 to limit the swinging movement of said latch relatively to said lever.

To the flange 18 is pivotally connected, at 70 29, the lower end of a link 30 which extends upwardly through an aperture 31 at the top of compartment 2 to the exterior 75 of tank 1, where its upper end is pivotally connected to an arm 32 fastened on the rear end portion of a rock-shaft or rod 33 which extends horizontally lengthwise of tank 1, at the top of the latter. The rear end of 80 shaft 33 is journaled in a bracket 34 secured to the top of tank 1 while forward of said bracket 34 the rock-shaft or rod is journaled in another bracket 35. Near the said bracket 35 the rock shaft or rod 33 is provided with 85 an arm 36 having a pin-and-slot connection 37 with one arm of a lever 38 fulcrumed at 39 upon bracket 35. The other arm 40 of lever 38 is bifurcated and straddles a collar 41 fast upon the upper end of a link 42, said 90 collar being made with an annular groove into which project studs 43 on arm 40.

It will now be clear that when lever 16, Fig. 3, is swung on its fulcrum pin 17 it acts through link 30, arm 32, shaft 33, arm 95 36, and lever 38 to move link 42 vertically. This link 42 extends downwardly from lever 38 through a stuffing box 44 into compartment 3 of tank 1 to near the bottom of the latter where its lower end is pivotally connected by a pin 45, Fig. 7 with a valve engaging lever 46. Lever 46 is fulcrumed at 47 upon an arm 48 forming part of a valve body 49 that occupies a hole provided in the bottom of the tank to which latter said body may be brazed, welded or otherwise secured. The stuffing box 44 is made with a radially extending annular flange 50 to which the bracket 35 is fastened by means of a screw 51, the body portion of said stuffing box being exteriorly threaded and screwed into a threaded opening in the top of tank 1.

Near its free end the lever 46 is made with a hole through which extends the threaded stem 52 of the shut-off valve 53, the latter being adapted to close downwardly on to a seat 54 provided upon body 49. Valve 53 controls an outlet port 55 formed through body 49 said outlet port being connected by a delivery pipe 56 with a manifold 57 105 to which the faucets 9 are connected each by a pipe 10.

Nuts 59 and 60 are adjustably mounted upon the threaded stem 52 above and below the lever 46, adapted to be engaged by the latter so as to move the valve from or toward its seat when the lever is actuated.

To the valve engaging lever 46 is fastened one end of a leaf spring 58 which extends under fulcrum pin 47 with its free end rest-

ing upon the bottom of tank 1 so that said spring is under a normal initial stress which tends to hold shut-off valve 53 on its seat, the said spring assisting in returning the 5 valve to said seat in the closing of the valve, and operating also to secure complete seating. The spring 58 is permitted to perform these functions by providing back-lash or lost motion at pin 45, studs 43, and pin and 10 slot connection 37 and other joints in the operating connections.

When the latch 21 occupies the notch 19 of the flange 18 of lever 16 the latter occupies a vertical position wholly within the 15 compartment 2 and just back of the plane of the doors 5 with the parts connecting said lever with lever 46 positioned so as to permit spring 58 to hold the shut-off valve 53 on its seat, pin 29 being then at the limit of its upward movement. In order to open the 20 shut-off valve 53 when delivering to a customer, it is necessary to unlock the doors 5, swing latch 21 to the limit of its movement toward the right, Figs. 1 and 5 to unlock lever 16, and then swing lever 16 outwardly into the horizontal position indicated by dotted lines in Fig. 4 where it is 25 automatically caught and held by the engagement of latch 21 with notch 20. It will be clear that so long as lever 16 occupies its 30 "open" position indicated by dotted lines in Fig. 4, the door 5 nearest said lever cannot be closed, and that after the driver has returned the measure to compartment 2 he 35 must first operate latch 21 to unlock lever 16 and then return the latter to its "closed" 40 position shown in full lines before he can close and lock the doors 5, this return movement of lever 16 acting through the connections described to effect the closing of shut-off valve 53. It will further be clear that 45 should the lever 16 occupy any intermediate position between the dotted line position in Fig. 4 and the full line position, with the outlet valve only partially closed, the corresponding door in being closed will press 50 against said lever and will actuate the lever into its said full line position, thereby operating to close the outlet valve through the closing movement of the said door. As the lever 16 arrives in its full line position in 55 Fig. 4 the latch 21 automatically becomes engaged therewith to again lock lever 16 and the outlet valve with the latter in closed condition.

My invention provides simple and reliable means for ensuring the closing of shut-off valve 53 after each delivery so that accidental or malicious opening of a faucet, or injury to a faucet or its pipes, cannot effect the discharge of the contents of the tank 1. Also, in the case of leaky faucets, wastage is prevented. An advantage of the construction above described is that the shut-off valve is operated by the driver through

means within his reach from his position upon the ground at the rear of the vehicle whereas, heretofore, it has been necessary for him to climb up upon the vehicle in order to reach and operate said means. Owing to the arrangement of the lever 16 within the compartment 2 the door of the latter cannot be closed except when said lever occupies its closed position. Furthermore, the position of the lever 16 serves to inform the 75 driver as to the condition of the shut-off valve whereas with the old construction there was no way of determining whether said valve was open or closed except by close examination of the valve operating means or 80 through discharge or leakage at the faucets.

It is desirable to have the shut-off valve closed at all times between deliveries so that in case of accident the delivery line will be closed and none of the gasoline or other 85 liquid is lost, thus eliminating the danger of fire and explosion in the street. Also, the shut-off valve being normally closed none of the contents of the tank 1 can leak out if either the faucet or the delivery line itself, 90 is damaged. It sometimes happens that while "on the road" a faucet starts to leak because of the seat of the faucet valve becoming worn. These seats are made of textile fabric composition and occasionally give 95 out so if the shut-off valve is open there is leakage at the faucet. This leakage cannot occur with the construction above described. Where the shut-off valve operating means is located on top of the tank the same is operated infrequently so that when it is necessary to close said valve, as in the case of damage to the faucet or pipe line, said means is sometimes found to stick through becoming "frozen." Constant use of the valve operating means of my improved construction 100 keeps the same in perfect working condition.

What I claim is:

1. A vehicle of the class described having, in combination, a tank body provided with 110 an outlet; a shut-off valve controlling said outlet; a storage compartment for measures; a movable closure for said compartment; and manually operated means for opening and closing said shut-off valve and for holding 115 said closure in open position while said valve occupies its open position.

2. A vehicle of the class described having, in combination, a tank body provided with an outlet; a shut-off valve for controlling 120 said outlet; a storage compartment for measures; a movable closure for said compartment adapted to occupy open and closed positions; a manually operated member by means of which to open and close said shut-off valve; and means connecting said member 125 and valve, said member being arranged so as to occupy a position out of the path of said closure when said shut-off valve is in its closed position and to occupy a posi- 130

tion in the path of said closure when said valve is in its open position.

3. A vehicle of the class described having, in combination, a tank body provided with 5 an outlet; a shut-off valve for controlling said outlet; a storage compartment for measures; a movable closure for said compartment adapted to occupy open and closed positions; a manually operated member by 10 means of which to open and close said shut-off valve; means connecting said member and valve, and means for holding said member in its different positions, said member being arranged so as to occupy a position 15 out of the path of said closure when said shut-off valve is in its closed position and to occupy a position in the path of said closure when said valve is in its open position so that said closure can occupy its 20 closed position only when said member is in position to close said shut-off valve.

4. A vehicle of the class described having, in combination, a tank body provided with an outlet; a shut-off valve for controlling 25 said outlet; a storage compartment for measures and the like; a movable closure for said compartment adapted to occupy open and closed positions; a manually operated member by means of which to open and close 30 said shut-off valve; means connecting said member with the shut-off valve; a gravity latch automatically engaging said member to hold the latter in its different positions, said member being arranged so as to occupy 35 a position out of the path of said closure when said shut-off valve is in its closed position and to occupy a position in the path of said closure when said valve is in its open position so that said closure can occupy its 40 closed position only when said member is in position to close said shut-off valve.

5. A vehicle of the class described having, in combination, a tank body provided with an outlet; a shut-off valve for controlling 45 said outlet; a storage compartment for measures and the like; a movable closure for said compartment adapted to occupy open and closed positions; a manually operated member within said compartment by 50 means of which to open and close said shut-off valve; and means connecting said member and valve; said member being arranged so as to occupy a position out of the path of said closure when said shut-off valve is 55 in its closed position and to occupy a position in the path of said closure when said valve is in its open position.

6. A tank wagon having in combination, a tank body provided with an outlet; a shut-off 60 valve controlling said outlet; a storage compartment; a movable closure for said compartment, and means controlled by said closure for operating said shut-off valve.

7. A tank wagon having in combination, a 65 tank body provided with an outlet; a shut-

off valve controlling said outlet; an operating member for said valve; a compartment; and a movable closure for said compartment, said member being operable to open 70 said valve only when said closure is opened and said closure being movable into its closed position only after said member has been shifted to close said valve.

8. A tank wagon having in combination, a 75 tank body provided with an outlet; a shut-off valve controlling said outlet; a compartment; a movable closure for said compartment, and a valve operating member engaged by said closure when the latter is moved toward its closed position while said 80 valve is in its open position.

9. A tank wagon having in combination, a tank body provided with an outlet; a shut-off valve controlling said outlet; a compartment; a movable closure for said compartment; and a member within said compartment and connected with said valve through which the latter is manually opened, said closure engaging said member when moved toward its closed position while the valve 90 is in its open position.

10. A tank wagon having in combination, a body provided with an outlet; a shut-off 95 valve controlling said outlet; a compartment; a movable closure for said compartment, and a member connected with said shut-off valve and co-operating with said closure to prevent the latter being closed while said valve occupies its open position.

11. A tank wagon having in combination, a body provided with an outlet; a shut-off valve controlling said outlet; a compartment; a movable closure for said compartment, and operating means for said shut-off 100 valve co-operating with said closure to permit of the latter occupying its closed position only when said shut-off valve occupies its closed position.

12. A tank wagon having in combination, a body provided with an outlet; a shut-off 105 valve controlling said outlet; a compartment; a movable closure for said compartment, and operating means for said shut-off valve co-operating with said closure to permit of said valve being opened only when 110 said closure is opened.

13. A tank wagon having in combination, a body provided with an outlet; a shut-off valve controlling said outlet; a compartment; a movable closure for said compartment, and an operating member for said 115 shut-off valve operable to open the valve only when the closure is in open position, said operating member occupying a position 120 in the path of said closure when said valve is in its open position.

14. A tank wagon having in combination, a body provided with an outlet; a shut-off 125 valve controlling said outlet; a compartment; a movable closure for said compartment; a 130

ment, and an operating member for said shut-off valve located within said compartment and movable into the path of said closure when shifted to open the shut-off valve.

15. The combination with a vehicle tank having a bottom outlet, and a box at one end of the tank having a door, of a valve adapted to close said outlet, and operating connections passing from the valve to the box and there having means whereby the valve must be closed when the door is closed.

10 16. A tank wagon having, in combination, a body provided with an outlet; a shut-off valve controlling said outlet; a compartment; a door for said compartment, and operating means for said shut-off valve co-operatively associated with said door so as to ensure a closed position of said shut-off

20 valve when said door is closed.

17. The combination with a vehicle tank having a bottom outlet and a pipe leading rearward therefrom and terminating in a dispensing faucet, and a bucket-box at the 25 rear end of the tank above the faucet, of an emergency valve commanding the bottom outlet of the tank, and means for controlling said valve from the interior of the bucket-box.

30 18. The combination with a vehicle tank having a bottom outlet, and a box at one end of the tank having a door, of a valve adapted to close said outlet, operating connections for the valve passing to the box, and means whereby the box and the valve may be closed simultaneously.

35 19. The combination with a vehicle tank having a bottom outlet, and a box at one end of the tank having a door, of a valve adapted to close said outlet, and operating mechanism for the valve having a member which must be moved to cause the closing of the valve in order that said door may be closed.

40 20. The combination with a vehicle tank having a bottom outlet, and a box at one end of the tank having a door, of a valve adapted to close said outlet, a valve-controlling handle inside the door, and connections whereby said handle is moved outward for 45 opening of the valve and inward for closing of the same, the handle requiring to be moved in in order that the door may be closed.

50 21. The combination with a tank having a bottom outlet, and a box at the end of the tank having a door, of a valve adapted to close said bottom outlet, and mechanism between said valve and door through which the door actuates the valve to bring about 55 the closing thereof.

55 22. The combination with a tank having a bottom outlet, and a box at the end of the tank having a door, of a valve adapted to close said outlet, and a train of operating connections for the valve having a member

arranged to be moved by the door in closing to cause closing of the valve.

23. The combination with a tank having a bottom outlet, and a box at the end of the tank having a door, of a valve adapted to close the outlet, a spring for seating the valve, operating mechanism passing from the valve to the box into cooperation with the door, and means for holding the mechanism and valve open.

75 24. The combination with a tank having a bottom outlet, and a box at the end of the tank having a door, of a valve adapted to close the outlet, a spring for seating the valve, operating connections passing from the valve to the box, means for holding the connections and valve open, and means whereby the door in closing actuates a member of the connections to cause the valve to close aided by the action of the spring.

80 25. The combination with a vehicle tank having a bottom outlet, and a box at one end of the tank having a door, of a valve adapted to close said outlet, operating mechanism passing from the valve to the box and there having a member which must be moved so that the valve is closed in order that the door may close, and means whereby the valve connections are automatically locked in the closed condition.

85 26. The combination with a vehicle tank having a bottom outlet, and a box at one end of the tank having a door, of a valve adapted to close said outlet, and operating mechanism passing from the valve to the box and there having means whereby the valve must be closed when the door is closed and whereby the valve is held in both its open and closed positions.

90 27. The combination with a vehicle tank having a bottom outlet, and a box at one end of the tank having a door, of spring-closing valve mechanism for said outlet, including operating connections passing from the valve to the box and there having means whereby the valve must be closed when the door is closed and means for holding the valve mechanism in the open condition while the door is open.

95 28. In combination with a vehicle tank provided with an outlet, and a box at the end of the tank having a door, a valve commanding said outlet, a lever in said box, and operating connections between the lever and the valve, the lever requiring to be moved into position in which it obstructs the closing of the door in order to unseat the valve.

100 29. In combination with a vehicle tank provided with an outlet, and a box at the end of the tank having a door, a valve commanding said outlet, a connection passing upward from the valve through the top of the tank, a control rod connected therewith and extending lengthwise over the top of

95

105

110

115

120

125

130

the tank, and means passing from the control rod into the box into operative relation to the door.

30. In combination with a vehicle tank
5 provided with an outlet, and a box at the end of the tank having a door, a valve commanding said outlet, a connection passing upward from the valve through the top of the tank, a control rod connected there-
10 with and extending lengthwise over the top of the tank, and a lever in the box connected with the rear end of said control rod.

31. In combination with a vehicle tank

provided with an outlet, and a box at the end of the tank having a door, a valve commanding said outlet, a spring for seating said valve, operating mechanism extending from said valve to the interior of the box and there having a handle which in the open condition of the valve obstructs the closing of the door, and a catch for holding said mechanism in the open condition against the closing action of the valve spring. 15 20

ANDREW F. ROBINSON.
